UNITED STATES PATENT OFFICE.

JACOB W. LATTIG, OF GLENSIDE, PENNSYLVANIA, AND CHARLES L. GOODRUM, OF URBANA, OHIO, ASSIGNEES, BY MESNE ASSIGNMENTS, TO WESTERN ELECTRIC COMPANY, INCORPORATED, A CORPORATION OF NEW YORK.

AUTOMATIC TELEPHONE-EXCHANGE SYSTEM.

1,355,983.

Specification of Letters Patent. Patented Oct. 19, 1920.

Application filed September 11, 1909. Serial No. 517,312.

To all whom it may concern:

Be it known that we, JACOB W. LATTIG, a citizen of the United States, residing at Glenside, Montgomery county, Pennsylvania, and CHARLES L. GOODRUM, a citizen of the United States, residing at Urbana, Champaign county, Ohio, have invented certain new and useful Improvements in Automatic Telephone-Exchange Systems, of which the following is a specification.

Our system relates to automatic telephone exchange systems and more particularly to that class of automatic exchanges in which a two-movement, or what has been termed the up-and-around, switch is used for each subscriber's line for making connections, the subject matter of the present application except as to certain details being disclosed in our application Ser. No. 222,657, filed August 29th, 1904.

It was common at the date of our original application to employ automatic switches in which wipers on a vertical shaft were arranged to contact with terminals in banks to which various subscribers' lines and operating circuits were connected, these switches being capable of a vertical movement to carry the wipers to different rows of contacts and a rotary movement to carry the wipers to different contacts in the horizontal rows. Systems employing such switches, however, had not been made commercially practicable in which central energy was employed at the exchange both for operating the switches and for talking purposes and one of the primary objects of our invention was to devise circuits and apparatus by which central energy could be employed with such a system and in connection with party lines, measured service, substations, repeating trunks, etc., these various features having been set out in the original application.

The particular feature to which the present application relates is the arrangement of circuits and apparatus for operating the switches at foreign exchanges or which are located at a distance and in which trunks are used for making connections from a switch at one exchange to another switch, or to substations in which the impulses from the subscriber's station are repeated through the said trunks to the controlling mechanism of the switches at the other or sub ex-

change, both in making the connection and disconnection of the said switches, the circuits and arrangements being such that they would be adapted to use either with or without the central energy.

A further object of the invention is to provide means by which either the called or the calling subscriber may disconnect the connected lines under different conditions, either at the close of the conversation or in case the called subscriber does not answer.

Further objects of the invention will appear from the description of the apparatus which follows and from the claims attached thereto.

In the drawings, Figure 1 is a diagrammatic view showing a subscriber's station and the connections from said station to the first selector switch which is individual to that line, also illustrating multiple connections for said subscriber's line to other switches, the switch here shown being for convenience hereafter termed the first selector switch. Fig. 2 is a diagrammatic view of the apparatus and circuits of the repeating trunks containing relays which repeat impulses coming from the subscriber's station through a first selector switch, which trunks lead to other switches which are generally arranged at remote distances, such as in other exchanges or sub-stations. Fig. 3 is a diagrammatic view showing the circuits and apparatus for the second selector switches which may be connected directly to the individual or first selector switches or by means of the trunks in Fig. 2, in which case they are connected through the repeating relays. Fig. 4 is a diagrammatic view showing the arrangement of the apparatus and circuits for the connector switches which are generally arranged in succession to the second selector switches, but which might be connected thereto by means of the repeating trunks, as shown in Fig. 2. Fig.

5 is a diagrammatic view of a subscriber's station and its first selector with the bank terminals of the connector, shown in Fig. 4, through which connection is made to said subscriber's station when it is a called station. Fig. 6 is a diagrammatic view showing the repeating relays and trunks permanently tied to a second selector switch, such as shown in Fig. 3, in which case the bank contacts, at the left of Fig. 3, are dispensed

with and the bank contacts to the left of Fig. 2 take the place of said contacts, all impulses passing to this selector switch or successive selector or connector switches being 5 repeated through the apparatus, therein shown, and also shown in Fig. 2.

In further explanation of the arrangement of the drawings it will be noted that Figs. 3, 10 4 and 5 are so arranged that the right edge 10 of one sheet is adapted to join on to the left edge of the succeeding sheet, which would give the ordinary connection, such as used in a single exchange, while Fig. 2 shows the arrangement of the repeating relays and 15 trunks to be used in case connection is to be made to a foreign exchange or a substation, for the purpose of repeating the impulses to the switches which are located at a distance, and Fig. 6 shows substantially the 20 same arrangement with the connection actually made, being, in effect, a consolidation of Figs. 2 and 3.

A brief outline of the system is as follows: Our talking circuits are metallic; that 25 is, each circuit is composed of two line wires. Each line comes into the exchange and is there connected to its first selector and also is connected to multiple contacts in several 30 banks of the connector switches. In addition to the two line wires an additional circuit or ground return is employed for sending impulses by means of which the switches are operated.

Each selector switch is a self-contained 35 unit, individual to its line and preferably contains a multiple contact for each of the second selectors in case the exchange has over a thousand lines, or for each connector in case the exchange has less than a thousand 40 lines. Each second selector is also a self-contained unit connected in multiple to the banks of the first selectors and each contains a multiple contact in its banks for each of the connector switches. Each connector is 45 a complete switch unit connected in multiple to the banks of the various second selectors in an exchange of over one thousand, or to multiple terminals in the first selector banks in case the exchange has less than a thousand, and 50 each connector also contains in its banks contacts for the subscribers' lines falling within its range, usually one hundred subscribers.

An outline of the method of selecting a 55 wanted subscriber is as follows: The calling subscriber, by impulses hereinafter described, causes the selector switch, individual to his line, to connect with an idle second selector in the set of second selectors containing the terminals corresponding to the 60 thousands digit in the number wanted. When such selection is made, the operating mechanism for his first selector is cut out of circuit, whereupon, by impulses from his 65 station, a second selector switch is operated

in a similar manner to connect with the terminal contacts of an idle connector in the group corresponding to the hundreds digit of the number wanted. The operation of this switch cuts off the operating mechanism of the second selector after which, by similar impulses from the calling station, the connector switch is automatically operated to select a multiple terminal of the particular subscriber's line wanted. As the 70 connection progresses step by step through the various switches, the metallic talking circuit of the subscriber calling is correspondingly extended through the first and second selector switches and the connector 75 switch. Means are employed, including condensers, by which the main battery is bridged across the circuit from the end toward the called subscriber but, until the latter answers, no battery flows to the calling 80 end. The signaling or impulses for operating the switches is accomplished over one or the other of the line wires and the ground connection.

The connection having been completed and the called lines not being found busy, the calling subscriber signals the called subscriber by pressing a signaling button at his station which operates a ringing relay in the connector circuit and thus applies a 90 ringing current on the wanted line. When the called subscriber answers, apparatus is automatically operated at the exchange by which battery is connected back to the calling end of the talking circuit. The switches 95 are released by the subscribers hanging up their receivers, a release magnet connected to each of the switches being operated automatically to restore the switches to their 100 normal position.

The description thus far relates to the circuits and the manner of making connections when the connections are to be made all within one exchange. Where connections are to be made to sub-stations, or groups of 110 subscribers at a distance, repeating relays are placed in the line by which the impulses from the calling station are repeated to the switches which are to be operated at the sub-stations or remote groups. In case of a 115 complete sub or branch exchange with first and second selectors and connector switches, these repeating relays would be placed in trunks leading from the first selectors or the switches individual to the lines to the second 120 selectors at another exchange. In other cases these repeating relays are placed in trunks leading from the individual or first selector to the connector switches, then the 125 said selector switches, as well as the connector switches, would be successively operated by means of the impulses from the subscribers' stations which are repeated successively to the selector switches and then to the connector switches.

Fig. 1 shows a pair of line wires 11-12 constituting a subscriber's line circuit and extending from the first selector or individual line switch, S, to the subscriber's station, A. Each subscriber's station is provided with the usual transmitter T, receiver R, induction coil i, switch hook H, ringer Q and condenser C. In addition to these usual instruments any suitable form of impulse transmitter is provided to successively ground the sides of the line for the purpose of sending impulses over the line, in a well known manner, this particular apparatus forming no part of our invention as such apparatus was in common use in what was generally known as the Strowger system. As before stated, our system is adapted to be used with the two-movement switches, which have a vertical and rotary movement, such switches being also common to the Strowger system and for this reason the different wires of the line circuit are usually termed vertical line and rotary line. These impulses are given by grounding the vertical side of the line a desired number of times, which is followed by grounding the rotary side of the line with a single impulse. Inasmuch as this is a decimal system the impulses necessary to produce a given movement of any switch will not exceed ten.

In the diagrams we have used the usual Strowger diagram of impulse transmitter in which an arm, a^2 , is adapted to move into engagement with a contact, a or a^1 , and thus ground either side of the line. It should be explained that the circuit breaker, a^2 , must be grounded when the impulses are being sent and in the Strowger apparatus means are provided for closing the circuit from ground to the lever a^2 by the movement of the calling dial and also for opening the branch including the talking instruments, otherwise both sides of the line would be tied together and both sides of the line would be grounded.

Receiver R is shown in a local circuit terminating in one winding of the induction coil, i, this being, in effect, the same as cutting off the receiver by a condenser so that battery current will not flow through it and its resistance is removed from the line. The transmitter circuit for a common battery or central energy system may be traced as follows: from vertical line wire 11, by branch 3, wire 25, wire 26, spring a^5 , spring a^6 , wire 24, springs a^{14} and a^{15} , one winding of induction coil, i, wire 23, transmitter T, and thence by wire 22, springs a^8 and a^9 , and wire 21, to the rotary side 12 of line through branch 4. The ringer, Q, is in a ground tap from branch 4, on the rotary side of the line with an interposed condenser C. The spring, a^4 , is grounded at G through resistance, r, for the purposes presently discussed.

It is to be understood that no substantial change is required in the subscriber's instrument to convert this system into a local battery system, the apparatus remains the same the only change being in the receiver and transmitter wiring and special battery at each sub-station.

The metallic talking circuit or subscriber's line wires, 11 and 12, pass to the first selector or individual switch, S, and terminate in the switch arms, f^1 and f^2 , of what is usually termed the side switch, F. This side switch comprises a series of arms, four in the case shown, which move together to successively engage a series of contacts, three of such contacts being shown, (Fig. 1) for each side switch arm. The side switch arms are marked respectively, f , f^1 , f^2 and f^3 . The arm, f , engages successively contacts, f^0 , f^{10} , and f^{20} , being normally in contact with f^0 . Similarly and synchronously the other arms move into engagement with their corresponding contacts during the operation of the apparatus, as hereinafter described, being normally in engagement with the contact, f^0 , in each case.

The vertical wire, 11, is normally connected through arm, f^1 , and wire 30, to the vertical relay, D, thence by wire 31, through cut-off springs k^3 , k^2 and k^1 and wire 32 to the main grounded battery, B, (shown in Fig. 3) 32 being the battery wire. The rotary side of the line or wire 12 is normally connected through arm, f^2 , by wire, 34, to the rotary relay, E, thence by wire 33, springs k^2 and k^1 , to wire 32 and thus to battery.

The main switch consists of a vertical spindle, v , which carries wipers or contact springs, v^1 and v^2 , which are adapted to successively engage and make connections with the bank contacts, m^1 and m^2 (Fig. 2). These bank contacts are arranged in horizontal rows, preferably of ten each. The banks of rows are curved in semi-circular form with a center in the axis of the vertical spindle, v . In order to bring the wipers into connection with any particular contacts, m^1 and m^2 , therefore the vertical spindle, v , is first stepped up or raised vertically until each wiper is opposite the desired row and then is caused to rotate step by step until the wipers make connection with the desired contacts or terminals in the row. The first movement of the spindle is called the vertical and the second the rotary movement.

It will be noticed that the wipers, v^1 and v^2 , are normally connected to the contacts, f^{20} , of the side switch arms, f^1 and f^2 , so that, in their normal condition with these side switch arms in connection with their contacts f^0 , the line wires, 11 and 12, are disconnected from the wipers v^1 .

The vertical relay, D, controls, through its

armature, a contact spring, d , which connects with a grounded contact, g , the spring, d , is connected by wire 37, through the springs, p^2 and p^1 , and wire 38, to the vertical motor magnet D^1 , thence by wire 38^a, to the main battery wire 32. This vertical motor-magnet, D^1 , is the magnet which actually steps up the shaft, v , or produces the vertical movement thereof.

10 The relay E, through its armature, controls the spring, e , which is adapted to close on the same grounded contact, g , the spring, e , being connected by wire 39 to what is called the private magnet P and thence to 15 main battery wire 32. From the wire 39 a branch 40 extends to the second contact f^{10} of the side switch arm, f^3 . When the side arm, f^3 , is on this contact the circuit would be continued through the back release relay 20 J to the private contact, v^2 , by wire 52. Normally, however, this magnet is cut off.

25 The relay, J, through its armature, j , controls the spring contacts, j^1 and j^2 , which, when the armature is attracted, close a circuit from ground by way of wire 41 to the release magnet, I, said magnet receiving current over the wire, 41^a, which is connected to the main battery wire 32.

30 It will be observed that the armature, p , of the private magnet, P, controls the springs, p^1 , p^2 and p^3 , the latter two of which also control a ground connection for the magnet, I, by way of wires 37^a, 37 and spring d . It is necessary, however, that the 35 magnets of both the vertical relay and the rotary relay P be energized in order to close this circuit as the private magnet, P, is controlled by the rotary relay E. This means that both the vertical and rotary 40 relays, D and E, must be simultaneously energized in order to close the release circuit. The private magnet, P, controls the side switch, F, in the usual manner. When the 45 release magnet, I, permits the parts to return to normal position, all the switch arms of side switch, F, are returned to normal position, as shown in Fig. 1. At each retraction of the armature, p , of the private magnet, P, these switch arms are all advanced one step by means of an escapement 50 not shown controlled by the said armature, p .

55 As before stated, each line has a first selector, such as shown in Fig. 1, with the individual selective wipers, v^1 , and these wipers are adapted to connect as the switch is operated with multiple contacts, m^1 . These multiple contacts, m^1 , represent the terminals of the wires 13 and 14 leading 60 to the various second selector switches. These wires, 13 and 14, represent trunk lines and, as the trunks are only used at any one time by a limited number of subscribers, they are less in number than the lines of the 65 first selectors, say, ten per cent. thereof.

The same may be said of the connectors which are further extended trunks. The multiple contacts, m^1 , in the first selectors represent terminals of lines leading to second selectors, and the multiple contacts in the second selector represent multiple terminals leading to the connectors, the multiple contacts in the connectors, however, are connected directly to the subscribers' lines and in multiple to their first selectors.

75 In the drawings Fig. 4 shows a connector switch whose multiple contacts, m^5 , see Fig. 5, represent terminals of different subscribers' lines or stations. The same connector would contain multiple contacts, m^5 , for example, for the line No. 1920 (see Fig. 5) and likewise would contain multiple contacts, such as m^9 , corresponding to the line 11-12 or station A (see Fig. 1) provided the said station were in the same hundreds division for which that connector switch is appropriated. The connector switches are arranged in groups and since the decimal system is used in the present case for convenience each group has multiple contacts or terminals of subscribers' lines or stations whose numbers all have the same hundreds digit, thus there will be one group of connector switches for subscribers from one to one hundred, another group for those from 101 to 200, another for from 201 to 300 and so on. In the same way the second selectors are divided into groups according to the thousands and each second selector has multiple terminals for all the connectors within 85 its thousand. Thus there will be multiples in one group of second selectors for all the connectors between one and one thousand; that is 100, 200, 300 and so on to 900 which selects up to 999. As already stated, if the 90 exchange is limited to one thousand or less, the second selectors can be dispensed with. In each first selector then every horizontal row of contacts would represent a separate hundred and each contact in that row a 95 separate connector switch in that one hundred group, all the connectors in one group being duplicates.

100 As before stated, Fig. 3 shows the second selector which, in its general construction, is similar to the first selector having a vertical shaft, v , wipers v^3 , v^4 , side switch F^1 , having the different arms, f^4 , f^5 , f^6 and f^7 , adapted to contact successively with the contacts f^0 , f^{10} and f^{20} , when operated by its 105 private magnet, P^2 , in the manner described for the first selector. The lines from the terminals, m^1 m^4 , of the first selector are represented by 13 and 14 and are tied to side switch arms, f^5 and f^6 . E^2 is the rotary 110 relay and D^2 the vertical relay of the second selector. The vertical relay, D^2 , is in a branch line 45 which leads from contact f^0 of side switch arm, f^5 , to the relay E^2 and thence to the battery wire 32. The rotary 115 120 125 130

- relay, E^2 , is in a branch 46 connected to contact f^0 of side switch arm, f^6 , to battery wire 32. Inasmuch as all the switch arms are normally on their contact f^0 , the vertical relay, D^2 , is normally connected to the vertical side of the line and the rotary relay, E^2 , is normally connected to the rotary side of the line 14, whereas the other terminals of both of these relays are connected to 5 grounded battery B. The armature of the vertical relay, D^2 , controls a spring, d^1 , and a mechanically connected but electrically separated spring, d^2 , which latter closes on the ground contact, g^1 , when the armature 10 is attracted. The armature of relay, E^2 , controls a spring, e^1 , and the mechanically connected but electrically separated spring, e^2 , which latter closes on the ground on contact, g^1 , when the armature is attracted. 15 The two springs, d^1 and e^1 , have curved ends adapted to come together and make electrical contact, when both armatures are simultaneously attracted, at the point, x , but not when either armature is attracted separately. 20

When the vertical relay, D^2 , is energized it closes a circuit through the vertical magnet, D^3 , from ground at contact, g^1 , spring, d^2 , contacts d^3-d^4 on the private magnet, 25 P^2 , vertical magnet, D^3 , to battery wire 32. When the rotary relay is energized it closes a circuit through the private magnet, P^2 , grounded contact g^1 , spring e^2 , private magnet P^2 thence to battery wire 32, thus energizing the private magnet P^2 to operate the side switch F^1 . 30

The release relay, J^1 , is in a circuit which extends from switch arm, f^7 to wipers, v^4 , of the second selector switch. The release 40 magnet, I^1 , for the second selector is in a circuit from battery wire 32, wire 50, magnet I^1 , wire 51, spring e^1 , spring d^1 , wire 47, wire 49, contact m^2 , wipers v^2 (Fig. 1) wire 52, release relay J , of the first selector, 45 switch arm f^3 , contact f^{20} to ground G, this circuit being normally open at the contacts, x , and at side switch arm, f^3 .

Fig. 4 shows the connector switch and apparatus and wires 15 and 16 which constitute the talking circuit are connected to the terminals, m^3 m^3 , of the second selector switch (Fig. 2) which are adapted to make connection with the wipers, v^3 . These wires include condensers, C^1 , so that the lines are 50 separated conductively but jointed inductively, the extension of the lines beyond the condensers being marked 15^a and 16^a . D^4 is the vertical relay and E^4 is the rotary relay. The vertical and rotary relays are in 55 a circuit from line 15, by wire 55, relay D^4 , wire 56, spring 57, contact spring 58, wire 61, spring 62, contact 63, wire 60 to rotary relay E^4 and thence to line wire 16. The relays D^4 and E^4 are thus bridged across the 60 line wires 15 and 16 through contacts 62 and 65

63 of the ringing relay, W , and 57-58 of relay, V , hereinafter described. Each is also supplied with a battery supply connection through spring 59 which is connected to battery wire 32. 70

The vertical relay, D^4 , through its armature, controls the spring, d^3 , and the mechanically connected but electrically separated spring d^4 , the latter closing upon the ground connection, g^2 . The rotary relay, E^4 , 75 through its armature, controls a spring, e^3 , and the mechanically connected but electrically separated spring, e^4 , also adapted to close upon ground connection, g^2 .

As stated, the rotary and vertical relays, D^4 and E^4 , are bridged across the lines 15 and 16. I also provide relays V and V^1 , which are bridged across the extended lines, 15^a and 16^a , with battery interposed through the following circuit: from wire 15^a , at 200, by wire 201 to relay V , wire 202 to ground, by ground to grounded side of battery B, battery wire 32, wire 203, relay V^1 , wire 204, to line wire 16^a at 205. The extended lines 15^a and 16^a , are connected through circuit 80 breakers operated by the ringing relay, W , to the side switch arms, f^{50} , f^{60} , and when cut through by the connector switch to the called subscriber, the relays V and V^1 will be bridged across the called subscriber's line and separated from the calling subscriber's line by the condensers, C^1 , so that these relays would be simultaneously energized by the closing of this end of the line when the called subscriber removes his receiver. Relay V however, through its armature, controls normally closed contacts while relay, V^1 , controls normally open contacts and by reason of the fact that the first movement of the armature in one case will open the closed contacts while there is an interval of time in movement of the armature, required to close the open contacts, that relay which is operating on the normally closed contacts will break the contacts before the other relay will close the normally open contacts although simultaneously energized and these relays are so arranged as to perform this function; that is to say, when they 90

are simultaneously energizing the one which is operating the closed contacts to open them will break the connection before the one which is operating the open contacts will close the connection and this is true whether the relays are being energized or deenergized, the closed contacts will always be opened before the open contacts are closed, when the relays are simultaneously energized or deenergized. The relay, V^1 , when energized, closes a circuit from line wire 15, through wire 76, spring 77, contact 78, and wire 79 to relay X and thence to ground; also a circuit from battery wire 32, by wire 71, relay Y , wire 72, spring 73, contact 74, wire 75, to the line wire 16, the battery B 100

110

115

120

125

130

being grounded the relays, X and Y, would thus be bridged across the line wires 15 and 16 with battery interposed. Battery would thus be supplied to each end of the line 5 separated by the condenser, C¹, upon the operation of the relay V¹. The rotary and vertical relays, D⁴ and E⁴, being bridged across the line through contacts 57 and 58, operated by the relay V, would be disconnected prior to the time that the relays, X and Y, are connected to this line, for the reasons before stated; that is, the relay, V, operating to break the contact would break the circuits for the relays, D⁴ and E⁴, before the circuits for the relays, X and Y, would be closed, although the relays are operated simultaneously. Relay X is adapted, when energized, to break the normally closed contacts, x¹ and x², while relay, Y, 20 when energized, is adapted to close the contacts, y and y¹. The making and breaking of these contacts has reference to the release circuit which will be hereinafter more fully described.

25 Attention is called to the fact, at this point, that the relays, X and Y, are similar to the relays, V and V¹, in that while they are simultaneously energized and operate simultaneously, the one which is operating on a normally closed contact will break that contact and thus break the circuit prior to the time that the one which is operating on a normally open contact will close the contact and thus close the circuit. This element of time between the opening of the normally closed contacts and the closing of the normally open contacts by simultaneously operated relays is essential to the successful operation of these circuits, as will 35 be more fully hereinafter described.

40 The armatures of the respective relays, D⁴ and E⁴, are provided with contacts, x, adapted to make electrical connection when both relays are operated simultaneously to close the circuit through the release magnet, J², in the manner hereinafter more fully described.

45 We will now assume a call to originate at A and describe the operation of extending this call to the station, A⁴, which we will assume is No. 1920: After taking down the receiver the subscriber operates his impulse transmitter to ground the vertical side of the line as many times as there are units in the thousands digit. In this case, assuming the number to be 1920, there would be one impulse only, but the impulse transmitter being so arranged that upon the conclusion of its operation it sends one impulse over 50 the opposite or rotary side of the line, we will have one impulse transmitted from ground over vertical side of line followed by one impulse from ground over the rotary side of the line. The first impulse over the 55 vertical side of the line energizes the verti-

cal relay, D, over the following circuit: From the grounded contact a², spring a, line 3, line 11, side switch arm f¹, contact f⁰, line 30, relay D, contacts k^a, k^b and k^c, to line 32, battery and ground. This energizes 60 the relay, D, which in turn energizes the vertical motor magnet, D¹, over the following circuit: grounded contact g, spring d, wire 37, spring p², contact p¹, wire 38, vertical motor magnet D¹, wire 38^a, wire 32 to 75 battery and ground. The energizing of the motor magnet, D¹, steps up the vertical spindle, v, as many steps as there are impulses, in this case there being but one impulse the vertical spindle, v, will be stepped up one 80 step or to the first thousand or to the bank representing selectors for the first thousand. As this impulse is followed in the transmitter by an impulse over the rotary side of the line, the relay, E, will be energized over 85 the following circuit: from grounded contact a², spring a¹, line 4, line 12, side switch f², wire 34, relay E, wire 33, contact k², contact k¹, battery wire 32, battery and ground. The energizing of the relay, E, 90 will energize the private magnet, P, over the following circuit: from grounded contact g, spring e, wire 39, relay P, wire 32, to battery and ground. This produces an impulse in the private magnet P which, through the 95 mechanical mechanism of the switch, operates the escapement mechanism to cause the side switch, F, to move over to the second position. This brings the switch arm, f, onto the second contact f¹⁰, which cuts in 100 the rotary motor magnet E¹, line 38^a, line 32 to battery and ground. This rotary motor magnet is so arranged that so long as it is in circuit it is operated by a vibrating current which causes the spindle to be 105 stepped around so long as current is supplied to said magnet. This continues until the wipers, v¹ and v², stop on an idle contact. This particular arrangement is common in switches of this kind and forms no 110 part of our invention. The result is, however, that when the wipers are started to rotate over a given bank to find a selector switch in the thousands represented by this bank, it will continue to operate until an 115 idle trunk is found when it will automatically stop and the side switch will be moved a second step or to the third position. The side switch is preferably so arranged that in moving from the first to the second position the vertical relay D is cut out by the switch arm f¹ and in moving from the second to the third position the rotary relay E is cut out by the switch arm f² in the usual way. When the side switch moves to 120 the third position both sides of the line, 11 and 12, will be connected to wipers, v¹ v², by the switch arms, f¹ and f², connecting with the contacts, f²⁰. This would connect station A to the second selector switch. The 125 130

calling subscriber again operates his transmitter to send nine impulses by closing contacts a^2 and a together nine times, which would be followed by closing the contacts, 5 a^1 and a^2 , together once. As before, the nine impulses will cause the vertical relay, D^2 of second selector to be energized nine times over a circuit from battery wire 32, through relay D^2 , wire 45, wire 13 back through wire 10 to the station A and ground and the relay, D^2 , is energized successively nine times and vibrates its armature nine times to ground the spring, d^2 , thereby closing the circuit of the vertical motor magnet, D^8 , 15 nine times which steps up the spindle, v , of the second selector switch nine rows or to the nine-hundredth row of connector contacts, m^3 . The single impulse that follows over the rotary side of the line 12 extended 20 to 14 passes through the rotary relay, E^2 , which grounds the spring, e^2 , and thereby closes circuit from battery wire 32, through private magnet P^2 , the latter opening the circuit for the vertical motor magnet, D^8 , at 25 contacts, d^3 and d^4 , and permitting the side switch, F^1 , to move all of its arms, f^4 , f^5 , f^6 and f^7 , to the second position, the arm, f^4 , cutting in the rotary motor magnet, E^3 , the arms, f^5 and f^6 , cutting out the relays, D^2 30 and E^2 . The arm, f^7 , connecting the wiper, v^4 , back through the relays J^1 and P^2 to the battery wire 32. The rotary magnet E^3 being in circuit vibrates and steps around the spindle, v , as before, until the wipers, v^3 35 and v^4 , find contacts of connectors that are idle or ungrounded. In this connection we should call attention to the fact that the instant the spindle, v , in Fig. 1 (first selector) commenced to rise, it released a spring, u , 40 (see the left hand side of Fig. 1) of a switch U , breaking circuit with contact, u^1 , of the bridge cut-off relay K , and grounding the wire 35 on the contact u^2 . This completed a partial circuit from ground as follows: 45 G , u^2 , u , 35, and to all the contacts, m^{10} , in the multiple banks of connectors upon which connection might be made with the line 11-12. These private bank contacts all being grounded will test busy therefore 50 if anyone else attempts to break in by calling line 11-12. Similarly, the instant connection was made between the first selector and the second selector at v^2-m^2 , and the side switch F of the first selector had moved 55 its second step or to the third position, ground on the wire 54 was connected to wire 53, magnet J , and wire 52 to the wiper v^2 and thence to all the connected multiple contacts, m^2 , of the second selector shown, 60 wherever they might be distributed, so that no first selector could get in on that second selector while thus in use.

As soon as the second selector finds a connector that is idle, the ground circuit 65 through magnet P^2 (Fig. 3) is broken, the

side switch, F^1 , makes its last step, the arms, f^6 , f^8 , complete the metallic circuit 13-14 onto 15-16, the arm, f^4 , cuts off the rotary magnet and thereafter remains open, and the arm, f^7 , closes the ground of contact, 70 f^{20} , onto the magnet, J^1 , and so to the wiper, v^4 , which being on the contact, m^4 , makes it and its connected multiple contacts of the connector thus selected test busy thereafter during the connection. 75

We have now reached Fig. 4, with a clean metallic circuit made up of wires 3, 11, 13, 15, on one side, and 4, 12, 14, 16 on the other side. This is the connector, which actually selects the contact of the line wanted. We 80 find the side switch, F^2 , present in this case also, and that it controls the circuits of three magnets, the vertical magnet D^4 , the rotary magnet E^4 , and the ringing relay W .

The subscriber now sends the number 2, 85 two impulses pass along the wires 15, 13, 11 and 3 and to ground at station A, through the connector circuit as follows: battery B to spring 59, to springs 58 and 57, relay D^4 , and wire 55 to wire 15. This vertical relay, 90 D^4 , then steps up the spindle, v , until its wipers, v^5 and v^6 , reach their respective second rows of subscribers' contacts. The single impulse that follows over the rotary side 95 16 of line causes an impulse of current from the battery B by wire 32, springs 59-58, wire 61, springs 62-63, wire 60, to relay E^4 , wire 16, and back to the subscriber's station. Relay E^4 grounds the spring, e^4 , closing the circuit of the private 100 magnet, P^3 , which opens contacts p^5 and p^6 and closes the contacts, p^7 and p^8 , thereby closing a circuit from the middle contact f^{10} , of the lower side switch arm, f^{10} , back 105 through the release magnet, J^2 , and to the battery wire 32. In moving its armature the magnet, P^3 , lets the side switch go around one contact, cutting in the rotary magnet, E^5 , and connecting the wiper, v^6 , 110 through the arm, f^{10} , and contact, f^{10} , back to the release magnet as stated. The subscriber now sends the number 0, which is ten impulses over the vertical side of the line. This again works the vertical relay, 115 D^4 , as before, which grounds the spring, d^4 , thereby closing a circuit from ground to spring g^2 and d^4 and thence by way of wire 64, spring p^5 and p^6 , arm f^{10} , rotary magnet E^5 , wire 67 and 32 to battery. The impulse 120 transmitter after sending the ten impulses for the numeral 0 over the vertical side of the line grounds the rotary side, as usual, causing E^4 to operate and in turn operate P^3 by energizing the following circuit: battery B, wire 32, magnet P^3 , springs e^4 and g^2 to ground. This action has brought wipers v^5 and v^6 onto the contacts m^5 and m^6 in the bank of the connector shown in Fig. 5 and the side switch has connected 125 lines 15^a and 16^a to the wipers v^5 through 130

side switch arm f^{50} and f^{60} and has connected the wiper v^8 to ground through the side switch arm f^{70} . If this line is busy there will be a ground on the contacts, m^6 , 5 by reason of the switch, U, in Fig. 5 being up against contact, u^2 , or by reason of m^6 being connected in multiple to another connector switch and therefore the instant these contacts, m^6 , are touched P^8 being energized 10 a circuit is completed from the battery, B, through the magnet J^2 , Fig. 4, which attracts its armature and releases the stop pawls which retain the spindle, v , in its rotated and elevated position, restoring the 15 connector to zero. If the spindle, v , of the connector had not already been restored to zero the magnets, D^4 and E^4 , would act when the calling subscriber initiates the release. These close their contact springs, 20 d^3-e^3 , at point x , whereby the following circuit is completed: battery B, wire 32, J^2 , e^3 , d^3 , to contact m^4 , wiper v^4 , magnet J^1 , arm f^7 , contact f^{20} and ground. The magnets, J^1 and J^2 , both act, the latter to restore the connector, S^2 , and the former to 25 close the circuit B, 32, 50, I^1 , 51, 49, m^2 , v^2 , 52, J, 53, arm f^8 , contact f^{20} , 54 and ground. Whereupon the magnet, I^1 , pulls out the pawls that hold the spindle, v , of the second 30 selector, S^1 , (Fig. 2), and restores this to zero; while the relay J closes the circuit of the release magnet, I, as follows: battery B, 32, 41 ^{a} , I, 41, j^1 , j^2 , and to ground. Whereupon magnet, I, pulls out the pawls 35 from the spindle, v , of the first selector (Fig. 1), S, and permits that to go to zero. The magnet I, magnet I^2 and magnet J^2 in each case when releasing the pawls from the vertical spindle also pull over the side 40 switch, F, F^1 or F^2 to the normal or zero position shown in the figures. When the spindle, v , of the first selector, S, drops down it takes the ground off the wire 35 by pushing down the spring, u , of the 45 switch U. Thus all parts are again normal and all switches idle.

Suppose, however, that the line wanted does not test busy. The subscriber after sending in his last number presses his ringing button, which closes together the springs, a^{13} and a^{14} , to ground the vertical side of line as follows: G, r, springs a^4-a^5 , a^{18} , a^{14} , a^6 , a^5 and by wire 25 to the vertical side of line. This permits current to pass back from battery wire 32 in Fig. 3 through vertical relay D⁴ to the subscriber's station and ground. The spring, d^4 , is again grounded, and circuit completed from ground through springs, p^5-p^6 , and wire 65 to arm f^{40} , contact f^{20} , wire 69, the ringing relay W and battery by wire 203. This relay attracts its armature and throws down the springs thereof, opening the vertical side of line 15^a entirely. It also opens the rotary side of line 16^a at spring 71 and connects the

said spring with the terminal of the ringing generator wire 170. Current then passes out through contact m^{51} , wire 18, wire 20, ringer Q¹ and to ground through the condenser at the wanted or called station. After ringing the calling subscriber, A lets go his calling button, the vertical relay D⁴ and ringing relay W are deenergized. The armature springs of relay W close the line contacts and a metallic talking circuit is cut through from calling station A to the called station A⁴ through the interposed condensers C¹ with all magnets, relays and ground connections removed from the talking circuit except that relays D⁴ and E⁴ with grounded battery connected therewith are bridged across the calling end of the line 15-16 through the contact springs 57-58 of relay V and the relays V and V¹ with battery interposed are bridged across the called end of the line 15^a and 16^a. Calling subscriber answers by removing his receiver from the switch hook which thereupon closes his metallic talking circuit 15^a and 16^a and thus simultaneously energizes relays V and V¹, bridged across the line with battery interposed. Relay V opens contacts 57, 58 and 59 and thus opens the circuit of the vertical and rotary relays D⁴ and E⁴. While relay V¹ closes contacts 73, 74, 77 and 78, thus closing the circuits of relays X and Y from battery to ground and thus simultaneously energizes the said relays X and Y. The opening of the contacts by relay V precedes the closing of the contacts by relay V¹ as and for the reasons heretofore described. Relays X and Y will by the operation of relay V be bridged across the calling end of the line with battery interposed, and this feeds battery to the calling end of the line 15-16, at the same time these relays being simultaneously energized the normally closed contact x^1 and x^2 will be opened by relay X followed immediately by the closing of the normally open contacts y y^1 by relay Y. At the conclusion of the conversation when subscriber A hangs up he breaks the metallic circuit and momentarily grounds both sides thereof by closing together the springs a^{10} , a^{11} and a^{12} , and relay X being connected from one side of the line to ground will be thus deenergized and relay Y being connected to the other side and to battery and ground will be energized, the released circuit is thus closed as follows: Battery B, 32, 250, J², 70^a, 70^b, y^1 , y , 70, x^1 , x^2 , 70^c, to the contact, m^4 , wiper v^4 , back release relay J¹, of the second selector, S¹, to the arm, f^7 , of the side switch, contact, f^{20} , ground and back to battery. Thereupon the release magnet, J², releases the spindle, v , of the connector switch, restoring the latter to normal; while the relay, J¹, closes the local circuit of the release magnet, I¹, of the second selector, S¹, and back through wire 49 to the release re-

lay J, of the first selector, which closes the local circuit of the release magnet, I of the first selector, and all the apparatus is released and returns to normal.

- 5 In case the called subscriber should hang up first, relays V and V¹ would be deenergized by the opening of the metallic circuit at the called subscriber's switch hook. This would cut out the relays X and Y by the 70
 10 opening of the contacts 73, 74, 77 and 78 by relay V¹, which would be immediately followed by the closing of the contact 57, 58 and 59 of relay V, which would close the circuit of relays D⁴ and E⁴ so that the last 75
 15 mentioned relays would again be bridged across the line with grounded battery, where upon when the calling subscriber hangs up his receiver the momentary grounding of both sides of the line would cause relays D⁴ 80
 20 and E⁴ to be simultaneously energized, by grounded battery flowing on each side of the line to ground at station A, which would close the release circuit at x. This would operate the release magnets and relays over 85
 25 the circuit just as described through contacts e⁸—d⁸ at Fig. 4 instead of through the line 70 and contact x¹ and x² and y and y¹ so that in either case the release would be effected by the calling subscriber hanging up 90
 30 whether the called subscriber has hung up his telephone or not.

We will now describe the operation of our trunking apparatus and the method of repeating calls to sub-stations or to remote 35 points.

Referring to Figs. 2 and 6 the trunk line here shown is adapted to form an extension from a given first selector in one exchange to a second selector in the same or a different exchange. The ends of the two wires, 13^a and 14^a in Fig. 2 are supposed to be connected to the wires 13 and 14 in Fig. 3, the release wire 119 of Fig. 2 being the same as release wire 49 of Fig. 3. Fig. 6 shows the 40 connection made, the extension in this figure being marked 13^a and 14^a. The trunk line is therefore to be considered as interposed between the first and second selectors, the two sides of the line which form the 45 trunk being broken by condensers C².
 50

The object of cutting the line by the condensers is, for the purpose of supplying a battery to each end of the line for the different subscribers, so that a subscriber on a 55 short line in conversation will not consume the current to the detriment of a subscriber on a long line.

For the purpose of obviating the effect of the discharge of these condensers the lines 60 are transposed, the purpose and operation thereof hereinafter set forth more fully. In Fig. 2 a double transposition is shown, but this is not necessary as the effect desired may be secured by a single transposition.
 65 In Fig. 6 we have shown the trunk repeat-

ing apparatus connected with only a single transposition of the line. In this figure the trunking lines 13^a and 14^a beyond the condensers C² taking the place of the lines 13 and 14 in Fig. 3.

In connection with the condenser, means are provided for feeding battery to the line wires on each side of the condensers for talking purpose and the calling or called 70 subscribers are furnished with talking battery from different sources, so that each talking instrument would have battery of 75 substantially the same potential, thus obviating the drop in the battery potential when the trunk is connected to another exchange or remote point; the direct current from the battery sources being stopped at the condensers while the alternate currents of the subscriber's transmitters would pass 80 through the condensers in conversation between subscribers. Inasmuch as the impulse to operate the switches are impulses of direct current which will not pass through the condensers it is necessary to provide for 85 passing these impulses around the condensers and for this purpose we provide repeating relays Z and Z¹ which are bridged across the lines 13 and 14 with battery connected thereto, connection being made through contacts adapted to be operated by 90 a relay Z⁵. In Fig. 2 this battery connection is shown from battery B² and in Fig. 6 the 95 battery connection is shown to the main battery B. It will be understood that the many batteries shown in the drawings are merely 100 for the sake of clearness, that in operation the main battery B may be used to take the place of these various batteries and a common return or metallic circuit will be made in the well known manner instead of the 105 various ground connections.

The repeating relays Z and Z¹ operate somewhat similar to the relays D⁴ and E⁴ of the connector switch in Fig. 4. That is to say, either one of said relays will be energized by the grounding of either side of the line and both will be energized by the grounding of both sides of the line. When either one is separately energized it operates an armature spring to engage a grounded 110 contact and when both are simultaneously energized by grounding both sides of the line, armature springs forming circuit closers are brought together for closing the release circuit as hereinafter described. The 115 armature springs 104 and 105 of relays Z and Z¹ are connected respectively to the lines 13^a and 14^a by wires 123 and 121, which pass around the condensers C² and therefore impulses which come over the lines 13 and 14 ground the lines 13^a and 14^a by the 120 operation of said relays and thus repeat the 125 impulses.

The transmission of impulses to the first selector and the selection of an idle trunk 130

through its contacts m^1 by a calling subscriber is exactly the same as heretofore described. The second set of impulses from the calling subscriber's, however, cannot 5 pass directly into the second selector being stopped by the interposed condensers C^2 . The impulses which come over the vertical line 13, however, will operate the relay Z over the following circuit from battery 10 (B in Fig. 2 or main battery B in Fig. 6) through contacts 94, 93 and 92 and wire 91, to relay Z , thence by wire 90 to line wire 13 and back to ground at the subscriber's station. This energizes relay Z and causes 15 its armature spring 104 to engage the grounded contact 108, which grounds the trunk line 13 a through wire 123, spring 104, contact 108 and ground. The grounding of trunk wire 13 a will operate to send an impulse 20 to the second selector switch in the manner heretofore described, that is to say the impulse will be repeated from wire 13 into the trunk 13 a and will energize the vertical relay D^2 from battery B, wire 32, relay 25 D^2 , wire 45, switch arm f^6 , line wires 13 a and to ground at 108 over the circuit last described. The single impulse that comes over the rotary side 14 of the line will operate to energize the relay Z^1 over the following circuit, battery (B or B ^{3}) contacts 30 94, 93, wires 96, relay Z^1 and wire 95 to line 14 and to ground at the subscriber's station. The energizing of relay Z^1 grounds its armature spring 105 on contact 108, thus 35 grounding the trunk or extension 14 a through wire 121 and this will operate the rotary relay E^2 of the second selector switch in exactly the same way as heretofore described by the grounding of the line 14 at 40 the calling subscriber's station when the trunk with the interposed condensers are not used, in other words the impulses will be repeated from line 14 to 14 a by relay Z^1 exactly the same as the impulses are repeated 45 from line 13 to 13 a by relay Z . After the second selector switch has been properly operated to find a connector switch, the connector switch will be operated by impulses from the calling subscriber's station repeated 50 by the relay Z and Z^1 in exactly the same way; that is to say these impulses from the calling subscriber's station over line 13 would cause the relay Z to ground the wire 123 of the trunk, and as 13 a is connected 55 through the second selector switch to line 15 of the connector switch, the vertical relay of the connector switch would be operated. The impulses coming over wire 14 would operate the relay Z^1 which would 60 ground the trunk or extension 14 a through the second selector switch to wire 16 of the connector switch and thus operate the rotary relay of the connector switch.

It should be noted that each impulse that 65 comes over the lines 13 and 14 will result

in the charging of the lines and consequently the charging of the condensers, connected thereto, with a subsequent discharge. If the lines 13—13 a and 14—14 a were connected straight through the condensers C^2 70 this charging and discharging of the condensers would tend to interfere with or neutralize the impulses transmitted over the line. To obviate this the lines are transposed, that is the trunk or extension 13 a is 75 connected to the condenser in the line wire 14 and the trunk or extension 14 a is connected to the condenser in line 13. The impulses are repeated from line 13 to trunk or extension 13 a around the condenser at 80 which time no impulses are passing over the line 14, the result of this is that the condenser that is being charged from line 13 discharges into trunk or extension 14 a while the impulses around the said condenser are 85 repeated into trunk or extension 13 a , while the discharge of the condenser which is charged by line 14 is into the trunk or extension 13 a the impulses from line 14 being repeated into the trunk or extension 14 a . Inasmuch as these impulses are transmitted 90 successively over the line wires 13—14 the discharge of the condenser is always into the side of the trunk or extension over which at the time no operating impulses are being 95 transmitted, so that no interference can take place. When the connection is established through the various switches for talking purposes the transposition of the line produces no effect, as the talking current will 100 flow over the lines and through the condensers the same whether transposed or not.

The connector switch having been operated to find the wanted subscriber the calling subscriber would press his ringing button as before to ground the vertical side of the line, which would energize relay Z to ground the trunk or extension 13 a , which would operate the ringing relay exactly the same as before described. The called subscriber answers by removing his telephone from the hook and the connection is made by metallic circuit between the calling and called subscriber.

Upon removing his receiver from the 115 hook the called subscriber will cause the operation of relay V^1 in Fig. 4 which will connect the battery B across the line 15—16 the same as before described. Owing, however, to the interposed condensers C^2 in the 120 trunk this battery current cannot pass back to the calling subscriber's station when the repeating apparatus is used. To obviate this we provide the relays Z^6 and Z^7 , which operate similarly to relays X and Y heretofore described. These relays Z^6 and Z^7 are connected in normally open circuits. One of said relays is adapted when its circuit 125 is closed to be connected direct to ground and the other relay is adapted when its cir- 130

cuit is closed to be connected to grounded battery. The circuit for relay Z^6 may be traced as follows: wire 113, contact 110 and grounded battery B, while the circuit for relay Z^7 is from line 14, wire 114, contact 109 direct to ground. Contacts 109 and 110 are opened and closed by the operation of a relay Z^2 in a circuit which may be traced from ground, wire 99, spring 101, contact 102, wire 100, relay Z^2 , wire 98, relay Z^6 , to grounded battery B. The circuit just traced is normally open at contact 102, but is adapted to be closed by armature spring 101, of a relay Z^3 , when this relay Z^3 is energized. This relay Z^3 is normally bridged across the trunk or extension 13^a—14^a by the armature springs 104 and 105 of relays Z and Z^1 , which normally engage back contacts 130 and 131 connected to wires 103^a and 103 which are connected to the terminal wires of the relay Z^3 . When the called subscriber closes his circuit by removing his receiver from the hook and thus cuts battery back to line 15—16, the relay Z^3 will be energized by this battery current flowing over wires 15—16 through contact m^3 — m^3 , wipers v^3 — v^3 , trunk extensions 13^a—14^a, wires 123—121, springs 104—105, contacts 130—131, wires 103^a—103 and relay Z^3 causing its armature spring to close against contact 102, which thus closes the circuit for and energizes relays Z^2 and Z^5 over the circuit heretofore described. The energizing of relay Z^5 opens the circuit of relays Z and Z^1 at contacts 92, 93 and 94 and the energizing of relay Z^2 closes the circuit of relays Z^6 and Z^7 . These relays Z^6 and Z^7 will thus be simultaneously energized but for the reason heretofore explained the normally closed circuit will be opened momentarily in advance of the closing of the normally open circuit, so that no release takes place at this time. Also relays Z^2 and Z^5 are similarly energized but Z^5 opens its contact prior to the closing of contacts by Z^2 , so that the repeating relays Z and Z^1 will be cut off of lines 13 and 14 and the relays Z^6 and Z^7 immediately thereafter will be connected to lines 13 and 14, relay Z^6 being in the branch 113 connected to grounded battery and relay Z^7 being in branch 114 which is connected direct to ground. As the calling subscriber has his receiver off the hook the subscriber's loop including lines 13 and 14 is closed, and consequently relays Z^6 and Z^7 are simultaneously operated as heretofore described. This circuit may be traced as follows: grounded battery, contact 110, wire 113, relay Z^6 , line wire 13 to calling subscriber's station and back over line 14 relay Z^7 , wire 114, contact 109, to ground. The battery current thus flows through these two relays Z^6 and Z^7 feeding the calling subscriber's end of the line with current for talking purposes whenever the

relays Z^6 and Z^7 are simultaneously energized.

This brings us to the release circuit between the switches when the repeating trunk is employed, with the interposed condensers. 70

So long as the called subscriber has not answered and therefore has not energized the relay Z^3 and thus cut off the repeating relays Z and Z^1 the simultaneous grounding of the two sides of the line by the calling subscriber hanging up would simultaneously energize the relays Z and Z^1 and would cause the armature springs 106 and 107 to close together in a manner similar to that heretofore described by the simultaneous 80 energizing of relays D^2 and E^2 . The circuit for energizing the relays Z and Z^1 could be traced as follows: from grounded battery, through wire 117, springs 107—106, wire 119, Z^8 , contact m^2 , wiper v^2 , wire 52, 85 to release relay J of the first selector switch as heretofore described. There is included in this release circuit in wire 119 a release relay Z^8 , which would be energized when the release for the first selector is closed. 90 The energizing of this relay Z^8 would simultaneously ground both sides of the extended line or trunk 13^a and 14^a through the armature springs 140—141 and wires 142—143, which connect to the trunk or extension lines 13^a and 14^a and this momentary grounding of both sides of the trunk line would operate the relays D^4 and E^4 and cause the release of the second selector and connector switches in the manner heretofore described. In case the connection has been completed by the called subscriber answering and the repeating relays Z and Z^1 have been cut out of circuit with the line wires 13 and 14 the release would be effected 100 through the relays Z^6 and Z^7 and their armature springs 115 and 116. When these relays Z^6 and Z^7 were simultaneously energized, armature spring 116 was opened and at the same time armature spring 115 was 110 closed, both of these contacts being included in a branch of the release circuit extending from line 117, contact 116, wire 120, contact 115, wire 122 to wire 119, in other words the release circuit is branched between wires 115 117 and 119, one branch includes the circuit closers 106 and 107 operated by relays Z and Z^1 and the other branch includes the circuit closers 115 and 116 operated by relays Z^6 and Z^7 . 120

As before explained when the relays Z^6 and Z^7 are simultaneously energized and de-energized either one or the other of their circuit closers will be open and the other one of said circuit closers be closed. Inasmuch as one of the relays Z^6 or Z^7 is connected from one side of the line direct to ground and the other relay is connected from the other side of the line to grounded battery the momentary grounding of both sides of 130

the line would cause the relay grounded side to be deenergized while the relay on the grounded battery side would remain energized, which would result in closing the release circuit at 115 and 116; in other words the grounding of the line 14 would deenergize relay Z^r , in the grounded branch 114 and which would therefore receive no battery current while the grounding of line 13 would keep the relay Z^s energized as it is in the branch 113 which includes the battery. The contact for the armature spring 116 is a back contact and closes when the relay Z^r is deenergized while the contact for armature spring 115 is a front contact and closes when the relay Z^s is energized. The result therefore of simultaneously grounding both sides of the wire is to close the branch 122 of the release circuit at contacts 115 and 116 and thus operate the release relay of the first selector switch or any switch which may be back of the contact m^2 over the line 119 which as before described includes the release relay Z^s of the extension or trunk 13^a and 14^a, and which being energized would momentarily ground both sides of the trunk 13^a and 14^a and thus release the second selector and connector switches as before described. Consequently the temporary grounding of both sides of the line by the calling subscriber when he hangs up his receiver will release all the switches whether the called subscriber has answered or not.

Having thus described our invention, we claim:

1. In a telephone exchange system, a metallic trunk circuit having condensers interposed in its two sides, a battery and controlling relays connected to the trunk at one side of the condensers and branches controlled by the relays leading to the other side thereof, the two conductors of the trunk circuit being transposed between the con-

densers and the point of connection to the branches.

2. In a telephone exchange system, two metallic circuits, condensers interposed in the sides of one of said circuits, means for repeating impulses from one metallic circuit to the other by causing the impulses transmitted over one side of one circuit to be repeated over the other side of the other circuit, and branch conductors for said impulses connected to the sides of the second-mentioned metallic circuit, said sides being transposed between the points of connection thereof with said branch conductors and said condensers.

3. In a telephone exchange system, two metallic circuits, condensers interposed in the sides of one of said circuits, means for repeating impulses from one metallic circuit to the other by causing the impulses transmitted over one side of one circuit to be repeated over the other side of the other circuit, branch conductors for said impulses connected to the sides of the second-mentioned metallic circuit, said sides being transposed between the points of connection thereof with said branch conductors and said condensers, a trunk release circuit, and means associated with said repeating means for controlling said release circuit.

In testimony whereof, we have hereunto set our hands this 6th day of Sept., 1909, and 31st day of August, 1909, respectively.
